FIG. 1 is a front elevational view of the cleaning device for pierced openings of the present invention, the rear view being a mirror image thereof;

FIG. 2 is a left side elevational view of the cleaning device for pierced openings of FIG. 1;

FIG. 3 is a right side elevational view of the cleaning device for pierced openings of FIG. 1;

FIG. 4 is a top plan view of the cleaning device for pierced openings of FIG. 1, the bottom view being a mirror image thereof; and,

FIG. 5 is a top, front perspective view of the cleaning device for pierced openings of FIG. 1.

The broken lines showing of an ear in FIG. 5 is for illustrative purposes only and form no part of the claimed design.
